UNITED STATES PATENT OFFICE.

DANIEL W. ROBERTS, OF CLEVELAND, OHIO, ASSIGNOR TO THE BILLINGS-CHAPIN COMPANY, OF CLEVELAND, OHIO, A CORPORATION OF OHIO.

MACHINE FOR DIPPING AND DRYING ARTICLES.

1,140,068.

Specification of Letters Patent. Patented May 18, 1915.

Application filed October 6, 1913. Serial No. 793,533.

To all whom it may concern:

Be it known that I, DANIEL W. ROBERTS, a citizen of the United States, residing at Cleveland, in the county of Cuyahoga and 5 State of Ohio, have invented a certain new and useful Improvement in Machines for Dipping and Drying Articles, of which the following is a full, clear, and exact description, reference being had to the accompanying drawings.

This invention relates to a machine for coating articles. Its object is to provide mechanism by which small articles of various shapes and sizes may be evenly coated 15 with great rapidity, doing away with the expense of dipping and draining them, as is the usual practice, and saving in the quantity of material employed, while producing a very even and finely finished surface.

20 The mechanism, in its preferred form, consists of a circular basket into which the articles are dumped, *en masse*; a tank surrounding the basket and containing the coating liquid into which the basket with the 25 articles may be immersed; and a rotatable device on which the basket is suitably mounted so that the articles may be rapidly revolved to throw off the superfluous liquid, thus producing an even coating. The basket 30 is removable from the rotatable mounting, so that it may be placed in a drier without removing the articles therefrom. This mechanism has various uses, among which may be mentioned its employment in connection 35 with the process of japanning described and claimed in my prior application No. 754,243, filed March 14, 1913.

Figure 1, in the drawings, is a side elevation of one form of my mechanism; Fig. 2 40 is a top plan, and Fig. 3 is a bottom plan of the same; Fig. 4 is a central vertical section through the basket and pan; Figs. 5 and 6 are details of means for attaching the cover on a basket.

45 The frame of the machine comprises a table having a rectangular top 10 suitably mounted on four legs 11 secured to the corners thereof. A tank 12 adapted to set loosely upon this table top, is open at the 50 top except for an inwardly turned flange 14 and has a closed bottom except for an opening 15 which is surrounded by an upright tube 16 securely mounted in this opening and extending upwardly nearly 55 the height of the tank. This opening and

sleeve are centrally located and surround a shaft 18 which is mounted in a bearing 19, rigid in the top 10. At its lower end this shaft is journaled in a bearing 20 formed at the center of a spider-like casting 60 21. This casting has four radiating arms 22 which are attached at their outer ends to the legs 11 thus providing effective braces for the legs and greatly adding to the rigidity of the frame, as well as supporting the 65 bearing 20. Mounted on the upper end of this shaft 18, is a substantially circular block 24 which carries four depending spring arms 25 having outwardly turned feet 26 at their lower ends standing normally just above the 70 surface of the liquid coating 28 in the tank 12, so that they may be rapidly rotated without coming in contact with the liquid.

The basket for containing the articles to be coated is indicated at 30 in Fig. 4. This 75 is preferably of metal, somewhat shallow and circular in form and has a central opening surrounded by an upturned sleeve 31 adapted to surround and be frictionally engaged by the arms 25, while allowing the 80 bottom of the basket to rest on the outwardly turned feet 26. These arms tend normally to spring outwardly, thus providing this frictional engagement whereby the basket may 85 be rotated.

Articles of various shapes and sizes may 90 be placed in the basket, as indicated at 33 without regard to the form or relative position, that is, they may substantially be dumped into the basket which is then covered by a flat sheet metal cover 34 having a central opening corresponding to the opening 95 in the basket except that it has notches 35 adapted to engage the arms 25, as shown in Fig. 2. This basket cover is held in place by small slidable bolts 36 held under pairs of strips 37 pressed from the sheet metal of the cover 34, each bolt having its middle portion bent into a loop, as at 39, which stands between the two strips 37, allowing 100 an endwise movement of the bolt while preventing it coming out entirely from under these strips. When the cover is in place the bolts are slid outwardly to engage eyes 40 mounted on the side of the basket.

To prevent the articles, which pile up 105 against the cover near its circumference, during the rapid rotation or spinning of the basket, from becoming marked or blemished by having some portion resting against the 110

flat surface of the cover plate 34, I provide a lining of wire mesh, for the under side of the cover, as indicated at 42 in Fig. 6. Now when the articles are placed in the basket 5 and the cover secured in position, they are then immersed in the coating liquid in the following manner: a pair of depending arms 45, one on each side of the tank, are pivoted to the tank at 46 and extend through 10 suitable openings in the top 10 of the frame. At their lower ends 47, they are pivotally connected to rock arms 48 rigidly mounted on the outer ends of a rock shaft 49, mounted in suitable brackets 50 secured to the 15 under side of the top plate 10. Another rock arm 52 is rigidly mounted at the middle portion of the rock shaft 49 and is connected by a link 54 with a foot lever 55, pivotally carried at its inner end by a 20 bracket 56 on the spider 21 and having at its outer end a suitable pedal 58. When this foot lever is depressed, it acts through the connections described to raise the tank 12, from the table, carrying the liquid upwardly, until the articles within the basket 25 are entirely immersed. This immersion is only momentary, immediately after which the basket may be rotated to throw off the superfluous liquid coating from the articles 30 and spread the remaining coating thinly and evenly. After this spinning of the basket, it may be removed from the arms 25, and taken to a baking oven or drier, where the articles are baked without removing them from the basket.

As a means for rotating the basket, I mount a pulley 60 on the shaft 18. As shown, this pulley is driven by a quarter turn belt 61, running over a pulley 62, (Fig. 40 2) mounted on a counter-shaft 64, carried in suitable hangers 66, which are secured to the floor adjacent the machine. I provide on this counter-shaft 64, a tight pulley 67 and a loose pulley 68, over which runs a 45 driving belt 70, driven from a suitable power shaft. To shift the belt from the loose pulley 68 to the tight pulley 67, to drive the counter-shaft, the shaft 18, and the basket, I provide a forked member 72 50 straddling one reach of the belt 70. This forked member is carried on a lever 73 pivoted at 75 to the under side of the table and may be operated by a handle 76 at the same side of the machine as the treadle 55. This 55 allows the operator to control the raising of the tank for immersing the articles, and the shifting of the belt for the application of power, from the same side of the machine.

The removal of the basket from the machine, allowing the articles to be baked without removing them from it, provides great convenience in handling the articles rapidly. By the use of a number of baskets, I find that articles of a wide variety of shapes and 60 sizes may be dipped and dried very rapidly,

one basket full of articles being placed in position in the machine as soon as another is taken out of it.

I also find that with some classes of articles and coatings the articles may be dried 70 by leaving them in the machine and spinning them for a longer time, the whirling of the articles enabling the air to dry them by evaporation.

Having thus described my invention, what 75 I claim is:

1. In a device of the character described, the combination of a cylindrical container for liquid, a basket within the container, a support for the container, a shaft carried by 80 the support extending through the bottom of the container and having spring supports carried by the shaft and adapted to engage the basket more tightly by centrifugal force when rotated, and means for rotating the 85 shaft to spin the basket.

2. In a device of the character described, the combination of a vessel for liquid having a side wall and central opening in the bottom, a sleeve mounted in said opening and 90 extending upwardly, a shaft extending through said sleeve, a support carried by said shaft and depending outside of said sleeve, and a basket having a central opening adapted to be engaged by said support, while 95 within said wall.

3. In a device of the character described, the combination of a vessel for liquid having a side wall and a central opening in the bottom, a sleeve mounted in said opening and 100 extending upwardly, a shaft within said vessel, depending arms carried by said shaft and springing outwardly, a basket having a central opening adapted to be engaged by 105 said arms, means for bringing the basket and liquid together and means for rotating the shaft while the basket is within said wall.

4. In a device of the character described, the combination of a cylindrical tank, a 110 support for said tank, a shaft mounted in said support and extending through the bottom of the tank, a sleeve mounted in the bottom of the tank surrounding said shaft, a basket within the tank having a central 115 opening, and a support adapted to removably engage said opening whereby the basket is held normally above the liquid, a pulley on said shaft, links pivotally attached to the sides of the tank whereby the tank may be raised to immerse the basket, and a treadle for operating said means.

5. In a device of the character described, the combination of a container for liquid having bottom and side walls and an opening in the bottom, a sleeve surrounding said opening, and extending upwardly within the container, a shaft within said sleeve, and spring arms carried by said shaft and depending around said sleeve.

6. In a device of the character described, the combination of a container for liquid having a bottom and side walls and an opening in the bottom, a sleeve secured to the bottom and surrounding said opening and extending upwardly within the container, a shaft extending through said sleeve, a support attached to said shaft and extending over the upper end of said sleeve and depending outside of said sleeve, a container adapted to be carried by said support, means for immersing said last named container in the liquid in the first mentioned container, and means for rotating the support.
7. A container for articles having an opening in its side wall, a vessel for liquid having a wall adapted to surround the container and having an opening in the bottom, a sleeve extending upwardly from said opening, and means for rotating the container extending upwardly through said sleeve and having a support comprising spring arms extending downwardly past the outside of

said sleeve, said support being adapted to engage the container and rotate therewith. 25

8. A container for articles having an opening in its side wall and having a central opening in the form of a sleeve, a vessel for liquid having a wall adapted to surround the container and having an opening in the bottom, a sleeve mounted in said opening, a shaft extending therethrough, a support carried by said shaft and depending outside the sleeve of the vessel and adapted to enter and engage the sleeve of the container, means 30 for rotating said shaft and support, and means for bringing the vessel and container together, the sleeve of the vessel being adapted to pass within the sleeve of the container. 35

In testimony whereof, I hereunto affix my 40 signature in the presence of two witnesses.
